Inventor.

Merritt F. Potter,

UNITED STATES PATENT OFFICE.

MERRITT F. POTTER, OF KANEVILLE, ILLINOIS.

IMPROVEMENT IN PORTABLE WASH-STANDS.

Specification forming part of Letters Patent No. 149,520, dated April 7, 1874; application filed November 19, 1873.

To all whom it may concern:

Be it known that I, MERRITT F. POTTER, of Kaneville, in the county of Kane and State of Illinois, have invented a Wash-Stand, of which the following is a specification:

The object of my invention is the formation of a wash-stand of more economical construction and more convenient than those heretofore made.

Figure 1 is a perspective, and Fig. 2 a sectional, drawing of my wash-stand, the same letters referring to like parts.

A is a bowl, perforated at the bottom and closed by the valve B. C is a hollow tube attached to and supporting the bowl, and also acting as a discharge-pipe for conducting the waste-water from the bowl into the vessel D beneath the base E. F is a wire attached at its upper extremity to the valve B and extending down through the tube C and bent upward at its lower extremity and terminating in the loop G outside the tube and above the base E. H is a cord extending from the bowl downward through the loops J J and attached to the loop

G. The ring K at the upper end serves for a handle.

To empty the bowl, I pull the cord upward, which raises the valve B, and the water escapes through the tube C into the vessel beneath.

For use in camp, the base E may be omitted and the tube C may be extended into the earth or inserted into another, which penetrates into the soil far enough to cause the absorption of all the water discharged through it.

I claim—

1. A portable wash-stand, consisting of a wash-bowl, in combination with a single tube which conducts the waste-water from the bowl downward into a receiver beneath, and is also the supporting-standard of the bowl itself.

2. In combination with the basin A, the valve B, having its stem passing down the basin-tube, and arranged to be operated from without, substantially as specified.

Witnesses: MERRITT F. POTTER.

EDW. W. DONN,
M. GARDNER.
